BEVERAGE DISPENSING VALVE UNIT OR SIMILAR ARTICLE

Peter B. Allard, Minnetonka Village, and Clark L. Lofgren, Brooklyn Center, Minn., assignors to The Cornelius Company, Anoka, Minn., a corporation of Minnesota

Filed Dec. 5, 1968, Ser. No. 14,817

Term of patent 14 years

Int. Cl. D15—99

U.S. Cl. D94—3

FIG. 1 is a front perspective view of a beverage dispensing valve unit showing our new design.

FIG. 2 is a top view thereof.

FIG. 3 is a rear view thereof.

FIG. 4 is a front view thereof.

FIG. 5 is a side view thereof, the opposite side having similar appearance.

FIG. 6 is a bottom view thereof.

The dominant features of our design reside in that portion of the article shown in FIGS. 2, 5 and 6 as lying left of the arrowed line, the center of the mounting sleeve of the article being broken away in FIG. 1 to indicate indeterminate length, and the end portion of said sleeve being broken away in FIGS. 2, 5 and 6 for convenience of illustration.

We claim:

The ornamental design for a beverage dispensing valve unit or similar article, substantially as shown and described.
